W. B. WALKER.

Broom Machine.

No. 11,451.

Patented Aug. 1, 1854.

UNITED STATES PATENT OFFICE.

WILLIAM B. WALKER, OF BENNINGTON, NEW HAMPSHIRE.

MANUFACTURE OF BROOMS.

Specification of Letters Patent No. 11,451, dated August 1, 1854.

To all whom it may concern:

Be it known that I, W. B. WALKER, of Bennington, in the county of Hillsboro and State of New Hampshire, have invented a 5 new and useful Improvement in the Manufacturing of Brooms and Brushes; and I do hereby declare that the following is a full description.

The nature of my invention consists in 10 compressing the broom corn or other material and forcing it into a chamber while in a compressed state.

The first part of the improvement or invention consists of one entire piece of casting, or otherwise formed, with chamber for 15 the reception of the material of which the broom is made.

This chamber is made of suitable depth 20 and dimensions for the purpose intended either with or without ledges or ribs on the inside for the purpose of better securing the material of which the broom is made on the opposite side of the chamber is a common socket for the introduction of a handle.

25 The part is represented on the accompanying drawing by Fig. No. 1.

The second part consists of two clamps with screws—as shown by the accompanying drawing Fig. No. 2—for compressing 30 the material. The first or main clamp is fastened to a suitable bench to which there are gages—as seen in Fig. No. 2—for keeping the material in its place. When there is sufficient material for a broom, it is screwed 35 down until sufficiently compressed. The other clamp as seen in Fig. No. 3 is movable and of the same thickness with the depth of the chamber; this clamp is put on and then screwed firmly down upon the projecting ends of the material; the ends being then cut off even with the outside, the outside clamp is taken off, and the ends extend into the chamber, which is driven up to the other clamp; the broom is now taken from the 40 clamp, and the third part introduced which consists of a chip.

The third part, as shown by the accompanying drawing Fig. No. 6, consists of a chip or thin piece of wood or other suitable 50 material, the narrow end about the width of the chamber and the other more or less wide as the width of the broom is required. After the material is forced into the cham-

ber the broom or brush is taken from the clamp and this chip inserted about midway 55 between the two sides of the chamber and sufficiently driven to confine the material in the chamber. This chip projects outward from the chamber more or less according to the length and stiffness of the broom required, and is of such a character that no precise length, width or thickness can be exactly specified. After the chip is inserted the broom is sewed in the usual form.

What I claim and wish to secure is—

The process of manufacturing brooms or brushes by compressing the material and forcing it into a chamber while in a compressed state, and securing it there by means of the chip or other device whereby the same 70 end is obtained.

That the material may be compressed by other devices than as described above, I am conscious from experiment; therefore it is the principle practically carried out 75 which I wish to secure by Letters Patent as well as the device by which it is done. The spring catch and trongs mentioned in my caveat filed, I consider as unnecessary.

WILLIAM B. WALKER. 80

E. B. WEST,
L. SMITH.

Nashua, in the county of Hillsboro and 85 State of New Hampshire, ss:

On the twenty-sixth day of January, A. D. 1854, before me, the subscriber, a justice of the peace for said county, personally appeared the within named WILLIAM 90 B. WALKER and made solemn oath that he verily believes himself to be the original and first inventor of the mode herein described for manufacturing brooms; and that he does not know or believe the same was 95 ever before known or used; and that he is a citizen of the United States.

E. B. WEST,
Justice of the Peace.
